UNITED STATES PATENT OFFICE.

JOHN SCHEMINGER, JR., OF PROVIDENCE, RHODE ISLAND, ASSIGNOR, BY MESNE ASSIGNMENTS, TO PETROLEUM HEAT AND POWER COMPANY, OF NEW YORK, N. Y., A CORPORATION OF DELAWARE.

ROTARY-GEAR PUMP.

Application filed April 17, 1924. Serial No. 707,269.

This invention relates to rotary gear pumps for pumping liquids and more particularly to rotary gear oil pumps.

Excessive wear upon the gears with consequent noise and increasing chatter resulting from their continued use, has long been an objectionable feature in pumps of this character. Such wear is known to be caused largely by films of oil adhering to the gear teeth, and unavoidably trapped therebetween under great pressure as the pump gears are rapidly rotated in opposite directions.

The object of this invention is to provide a rotary gear pump casing in which the oil congestion or intense oil pressure upon and between the gear teeth will be wholly relieved, thus eliminating the excessive wear thereupon.

Simplicity in construction, efficiency in operation, and inexpensive in cost of manufacture are further desiderata contemplated in my improved rotary gear pump.

This invention will first be hereinafter more particularly described, with reference to the accompanying drawings, which are to be taken as a part of this specification, and then pointed out in the claim at the end of the description.

In said drawings, Fig. 1 is a sectional side elevation of my improved rotary gear pump, the gears being shown in elevation;

Fig. 2 is an end sectional elevation of the same, taken on the line 2—2 of Fig. 1;

Fig. 3 is a plan elevation of the side plate of the casing taken on the line 3—3 of Fig. 2;

Fig. 4 is a fragmentary section taken on the line 4—4 of Fig. 3;

Fig. 5 is a fragmentary plan view of the side plate, illustrating a slight modification; and

Fig. 6 is a fragmentary section taken on the line 6—6 of Fig. 5.

Referring to the drawings in which like reference numerals are used to designate corresponding parts throughout the several views, 7 denotes a rotary gear pump casing, the inner walls of which are shaped to conform facially and peripherally with intermeshing pump gears 8 and 9, which are mounted on shafts journaled in the sides of the casing, the latter being driven by its extended shaft 10 from any suitable source of power, and the former in turn being rotatably driven by the latter gear with which it

engages. It will be noted that the walls of 55 the casing closely embrace the cooperable intermeshing gears in the usual manner in order that the pump may maintain a maximum efficiency in pumping the oil without leakage around the peripheries or sides of the respective gears. The pump casing (as shown) is securable to the floor or a fixed part of the mechanism or apparatus with which it is associated and formed with threaded openings in its top and bottom portions (above 60 and below the plane of the gears) for connection with oil admission and pressure discharge pipes 11 and 12 respectively.

One wall of the casing is formed as a removable side plate 13 in order to permit access to the gears for any desired purpose.

In one or both of the side walls of the casing as shown in Figs. 1 to 4 on a vertical line intermediate the axes of the gear shafts and substantially below the horizontal plane 75 thereof, is formed an elongated groove or recess 14 of Y-shaped form, which extends in the plane of the inlet and discharge ports and is of substantially the same depth its full length and has its open side facing the 80 intermeshing teeth of the gears with each branch of its forked end turned toward one of said shafts, so as to provide a vent or vents at the side or sides of the intermeshing gears at the point where their respective teeth 85 are consecutively engaged with each other as the gears are rotated; said vent or vents extending along said vertical line from near the point where the teeth engage to a point slightly above the axial centers of the gears 90 and terminating short of the point where the teeth are disengaged, thus facilitating the displacement of any oil that may adhere to the gear teeth or be trapped therebetween and relieving the pressure of oil upon and 95 between the engaging teeth and permitting it to escape from therebetween into the body or stream of oil being discharged from the pump casing under the impelling pressure of 100 the revolving gears.

Referring to Figs. 5 and 6, in which a slight modification is shown, 15 denotes an oblong recess substantially angular when viewed in cross section and of substantially the same depth its full length, which may be 105 formed in the side wall or walls of the casing instead of the Y-shaped groove 14 and arranged in the manner described with ref-

erence to the Y-shaped form to adapt it to perform the same function as the latter. However, the first described form is preferable and advantageous in providing a 5 forked end with each branch of the fork turned toward one of the gears in the direction of rotation thereof, so that any oil that may be trapped between the gear teeth may escape at the delivery end of the recess 10 along either of two diverging lines or channels, thus more effectually relieving the pressure as the gears rotate in the direction indicated by the arrows in Fig. 1.

The simplicity, advantages and value of 15 my improved gear pump casing in relieving the oil pressure upon and between the gear teeth and thus eliminating the excessive wear thereupon, will be obvious from the foregoing description, and it is therefore thought that 20 further explanation is unnecessary.

I am aware that it has been proposed to provide a rotary pump with a vent or by-pass in the side wall or walls of the housing, to permit the escape of water that may become 25 pocketed between intermeshing teeth of the gears, and I do not broadly claim any such construction.

Having thus described my invention, what

I claim as new and desire to secure by Letters Patent of the United States is:

A rotary gear pump comprising a casing 30 containing a pair of peripherally toothed intermeshing gears; said casing having oppositely disposed inlet and discharge ports extending in a plane intersecting the intermeshing teeth and an elongated recess in its inner side wall arranged at an intermediate point between the axes of said gears directly opposite said intermeshing teeth and extending along said plane from near the point where 35 the teeth engage to a point slightly above the axial centers of the gears and terminating short of the point where the teeth are disengaged; the delivery end of said recess being forked or bi-branched and each branch thereof extending in the direction of rotation of one of the gears; said recess being of substantially uniform depth throughout its length, whereby a relief vent is provided directly opposite the intermeshing teeth and in close 40 proximity thereto through which liquid may easily escape therefrom along converging lines.

In testimony whereof I affix my signature.

JOHN SCHEMINGER, JR.
